United States Patent Office

Des. 218,266
Patented Aug. 4, 1970

218,266

TACKLE BOX

Paul Belokin, Jr., 1603 Orrington Ave.,
Berwyn, Ill. 60201

Filed Apr. 25, 1968, Ser. No. 11,619

Term of patent 14 years

Int. Cl. D3—99

U.S. Cl. D87—1

FIG. 1

FIG. 2

FIG. 3

FIG. 4

FIG. 5

FIG. 1 is a perspective view of a tackle box showing my new design;

FIG. 2 is a top view thereof;

FIG. 3 is an end view thereof; and

FIG. 4 is a perspective view of the tackle box in open position.

FIG. 5 is a top view thereof in open position.

The bottom of the tackle box is represented in FIGS. 3 and 4 as flat and the side of the tackle box opposite that shown in FIG. 1 is substantially identical.

I claim:

The ornamental design for a tackle box, as shown and described.
